(57) **CLAIM**

The ornamental design for a smart phone stand with communication and lamp functions, as shown and described.

DESCRIPTION

FIG. 1 is a front perspective view of a smart phone stand with communication and lamp function showing our new design; FIG. 2 is a front view thereof; FIG. 3 is a rear view thereof; FIG. 4 is a right side view thereof; FIG. 5 is a left side view thereof; FIG. 6 is a top plan view thereof; FIG. 7 is a bottom plan view thereof; and, FIG. 8 is a sectional view taken along a line 8-8 in FIG. 2. The broken lines in the drawings are for the purpose of illustrating unclaimed portions of the smart phone stand with communication and lamp function and form no part of the claimed design.

1 Claim, 5 Drawing Sheets
